BOBBY PIN APPLIER

Filed Dec. 10, 1949

UNITED STATES PATENT OFFICE

2,600,711

BOBBY PIN APPLIER

Lew Wayner, Los Angeles, Calif.

Application December 10, 1949, Serial No. 132,285

2 Claims. (Cl. 132—1)

1

This invention relates to a device for applying hairpins to the coiffure.

Hairpins, and more specifically those of the bobbypin type, require that their open ends be initially spread before application, when dressing the hair. Bobbypins particularly, strongly resist such opening and frequently cause broken nails or chipped teeth, depending on whether the nails or the teeth are used as an aid to spreading the ends. Such crude methods are commonly employed, although many attempts have been made to provide spreading devices. While the latter are an improvement over nails and teeth, unless carefully handled, a finger will sometimes be pinched by the spread arms of the bobbypin seeking to return to closed condition. In other words, so long as the bobbypins are manually handled, whether or not spread by some mechanical aid, they comprise a hazard to the user. Also, their application by hand is time consuming.

Accordingly, the principal object of the present invention is to provide a device that may be charged with a quantity of bobbypins and operated, with ready facility, so as to discharge said pins singly and with their ends spread.

Another object of the invention is to provide a device, as indicated, that is designed to present the open bobbypins directly to the hair and at the different points of application, thus enabling placing the pins without manual handling thereof.

A further object of the invention is to provide a novel one-handed tool (thus leaving the other hand free to arrange the coiffure) that can be operated by a squeeze of the hand to eject a pin and simultaneously spread the ends thereof, the tool being so formed that said pin can be applied exactly where wanted.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a side elevational view, partly broken

2

away, of a preferred form of bobbypin applier according to the present invention.

Figs. 2 and 3 are opposite edge views thereof.

Fig. 4 is a face view, with certain parts removed, of the ejection end of the applier and shown in the process of ejecting a bobbypin.

Fig. 5 is a cross-sectional view as taken on line 5—5 of Fig. 4.

Fig. 6 is an enlarged perspective view showing a portion of the pin-ejecting means and the pin-end-spreading means of the applier.

The present bobbypin applier comprises a flat body 10 that embodies a magazine 11 storing a quantity of bobbypins and pin-ejecting means 12, operating means 13 for the pin-ejecting means, and a spreader 14 for the ends of the pins being ejected, said spreader being located in the path of movement of the pin, whereby successive operations of the operating means 13 eject pins successively.

The body 10 has a portion 15 adapted to be grasped in the hand. At the ejection end, the body is provided with an extension 16 of sufficient length to accommodate the ejection means 12 when in retracted position. On the edge opposite to said extension, the body is provided with a shorter extension 17 for housing spreader 14 and also the pivot 18 for the operating means 13.

The body 10 may be formed in various ways. As shown, the same comprises opposite side plates 19 and 20, a filler piece 21 spacing said plates at one end and along most of the edge that is on the side of extension 16, a filler piece 22 spacing the plates at the other end, and a relatively thin metal plate 23 between plate 19 and filler pieces 21 and 22. Suitable rivets, screws or the like 24 connect the above-named parts of the body in a generally conventional manner. Plates 19 and 20 and pieces 21 and 22 may advantageously be made of any of the synthetic phenolic resins or equivalents thereof. Thus, these parts may be inexpensively molded.

The magazine 11 is designed to store a quantity of bobbypins 25 in stack arrangement and comprises an elongated flat bar 26 affixed by rivets 27 to filler piece 22 and extending longitudinally of the body portions 15 between plates 20 and 23. A throat 28 is formed by notching the plates comprising the body so as to give access to bar 26, as best seen in Figs. 1 and 2. A follower 29 that has an extension 30 protruding through a longitudinal slot 31 in plate 20, follows behind the bobbypins 25 which are strung on bar 26. A spring 32, anchored at one end to extension 30 and at the other to a stud 33 on

filler piece 21 and extending through slot 31, urges follower 29 against the stack of bobbypins on bar 26. A retracting handle 34 is provided on extension 30 and, by means of said handle, the follower 29 is retractable to one side of throat 28 so that bobbypins, introduced therethrough and strung on bar 26, are projectable by the follower, when released, toward the end of the body that is provided with the ejecting means 12.

Said ejecting means may be variously formed. As shown, the same comprises a guide bar 35 that is affixed by rivets 36 to the inner face of body plate 20, and an ejecting slide 37 that is guided on bar 35. Said bar 35 extends transversely and at one end of body part 15, terminating at one end 38 adjacent spreader 14 and at the other end in extension 16. Bar 35 is provided with a face 39 against which the outermost bobbypin of stack 25 is pressed by follower 29, the stack being thereby confined between said bar and follower. It will be noted, particularly from Fig. 4, that bar 26 terminates at an end 43 that is spaced from bar face 39 a distance slightly greater than the width of a bobbypin. Thus, the outermost pin is adapted to be displaced in an endwise direction while the remaining pins remain on said bar 29. The slide 37 is shown as a channel-shaped member engaged over bar 35, the same being provided with an abutment lug 41 arranged to engage the closed bend 42 of the bobbypin that is against bar face 39. Said lug 41 is laterally extended into a recess 43 formed in the inner face of plate 19 and is adapted to travel therealong. Plate 23 is provided with a slot 44 through which said extension of lug 41 projects, as shown in Fig. 5. An opening 45 is formed in said lug extension for connection with the pin-ejecting operating means 13.

The filler pieces 21 and 22 space body plate 20 from metal plate 23 to define a body cavity 70 in which magazine 11 is disposed and in which the stack of bobbypins 25 moves toward ejecting means 12. Cavity 70, at the end of the body having extension 16, is transversely elongated to form a transverse passage 71 that is open at one end at the side edge of the body that carries spreader 14. The ejector slide 37 operates in said passage and guide bar 35 is longitudinally disposed therein.

The pins of stack 25 are held aligned and in flat engagement with the inner face of plate 20 by a pair of leaf springs 46 that are carried by plate 23. Assurance is therefore had that said pins will be guided to a desired position from which the same may successively be ejected in proper operative relationship to spreader 14.

The pin-ejecting operating means 13 comprises a lever 47 pivoted at 48 to body plate 19, a finger-engageable operating handle 49, carried by body portion 15 on pivot 18 and connected to said lever, and a return spring 50 carried by filler piece 22 and engaged with handle 49. The lever 47 has an end 51 that extends into opening 45 of lug 41 and an opposite end 52 that is engaged in a notch 53 in an arcuate portion 54 of handle 49. Lever 47 resides in a recess 55 provided in the inner face of body plate 19, said recess being somewhat shallower than recess 43. A suitable arcuate recess 56 in plate 19 is provided for lever portion 54. From Fig. 3 it will be seen that portion 54 is offset relative to the finger engageable handle portion 57 of handle 49 so that spring 50 may engage the inner face of the latter portion, since said spring is anchored in a slot 58 provided in filler piece 22 and is aligned with said

filler piece. Since lever 47 is of the first class, it will be evident that spring 50 will hold end 51 thereof retracted as in Fig. 1 and, that upon pressure exerted on handle portion 57, said end 51 will effect projection of slide 37 so that lug 41 of said slide will eject a bobbypin beyond the end 38 of bar 35. Figs. 4, 5 and 6 show partial ejection of such a pin.

The spreader 14 comprises a preferably metallic block 59 that is located between plates 20 and 23 and comprises part of extension 17. An end of the block is provided with a projection 60 that is in the path of ejection movement of a bobbypin. Said projection is of generally triangular or wedge shape, as can be clearly seen from Figs. 5 and 6. One side 61 of the projection is straight, parallel with the leg 62 engaged therewith and serves to guide said leg 62 of a pin without deflecting the same. The opposite and diverging side 63 of the projection is curved or, at least, angularly disposed from the apex 64 outward at a transversely sloping angle from the base of the projection 60 to the opposite side 61. Thus, side 63 is engaged only by an edge of pin leg 66. It will be evident that said apex will engage the curved end 65 of the other leg 66 of a pin to spread the same, as the pin is being ejected. This spreading action occurs whether or not leg 66 is provided with crimps.

So long as the major portion of a pin is being guided by bar 35, the next adjacent pin of the stack, springs 46, and the inner face of plate 20, the pin will move in a straight-line path. However, when most of the pin has been ejected, the curvature or slope of face 63 of projection 60, will tend to deflect leg 66 (now under considerable flexure) in a direction out of the normal path of movement of the pin and away from face 67 of block 59. Thus, when the pin has been projected clear of stack 25, the same will slip off projection 60 and the spring arms of the pin will automatically close.

In use, the present device is placed so that spreader 14 is at the point where a bobbypin is to be applied. The handle 49 is pressed to project a pin, which automatically opens while being projected and then automatically closes over the hair as complete ejection is achieved. After handle 49 is permitted to return to its initial position, the device is ready to eject a second pin to a desired point of the coiffure. Since the operation entails but the use of one hand, the other may be employed for arranging the tresses and for holding them in temporary place 55 while the pins are successively applied in the manner above suggested.

While the invention that has been illustrated and described is now regarded as the preferred embodiment, the construction is, of course, subject to modification without departing from the spirit and scope of the invention. It is therefore not desired to restrict the invention to the particular form of construction illustrated and described, but to cover all modifications that may fall within the scope of the appended claims.

Having thus described the invention, what is claimed and desired to be secured by Letters Patent is:

1. A bobbypin ejector comprising a flat body embodying a magazine for holding a quantity of bobbypins in stack arrangement, a spreader for said bobbypins at one edge of said body and adjacent one end thereof, an ejector within the body engageable by the topmost bobbypin of the stack and movable in a path to successively eject

pins from the stack toward and beyond said spreader, a handle disposed adjacent said edge of the body and having a portion extending into the body from said edge, a pivot connecting said handle to the body, and a lever within the body interconnecting said portion of the handle and said ejector and having a pivot intermediate its ends and connecting the lever to the body, the body and handle being adapted to be grasped in one hand and the handle pressed by the fingers of said hand in a direction toward the body to rock the lever on its pivot and move the ejector in a direction opposite to that of the movement of the fingers, whereby the bobbypins from the stack are ejected from the body in a direction opposite to the direction of movement of the handle.

2. A device for applying bobbypins directly to the coiffure, said device comprising a flat body adapted to be grasped in the hand and embodying a magazine for holding a quantity of bobbypins in stack arrangement, said body having a transverse passage near one end thereof and said passage being open at one end at the side edge of said flat body and open to the topmost bobbypin of the stack, an ejector slide in said passage provided with an abutment lug

10 15

engageable with the closed end of the topmost bobbypin of the stack, operating means interconnecting the body and the ejector slide and including a handle adjacent said side edge of the body and operable by the hand grasping the body to project the ejector slide in a direction toward the open end of the passage to cause said abutment lug to displace the topmost bobbypin, open end first, through the end of the passage, and a spreader carried by said side edge of the body beyond the open end of said passage and in the path of the bobbypins to spread the open ends of the latter during such ejection displacement of the bobbypins.
